DESIGN FOR A REFRIGERATOR TRUCK

Byron S. Snowden, Albany, N. Y., assignor to
General Ice Cream Corporation, Schenectady,
N. Y., a corporation of New York

Application November 18, 1937, Serial No. 72,989

Term of patent 14 years

To all whom it may concern:

Be it known that I, Byron S. Snowden, a citizen of the United States and a resident of Albany, in the county of Albany and State of New York, have invented a new, original, and ornamental Design for a Refrigerator Truck, of which the following is a specification, reference being had to the accompanying drawings forming part thereof, in which:

Fig. 1 is a side view of a refrigerator truck showing my new design.

Fig. 2 is a top view thereof.

Fig. 3 is a front end view thereof, and

Fig. 4 is a rear end view thereof.

I claim:

The ornamental design for a refrigerator truck, as shown.

BYRON S. SNOWDEN.
